UNITED STATES PATENT OFFICE.

MARSHALL BECK, OF MOLINE, ILLINOIS, ASSIGNOR OF TWO-THIRDS TO
JACOB W. SKINKLE AND DAVID K. HILL, OF CHICAGO, ILLINOIS.

MACHINE FOR GATHERING AND LOADING HAY.

SPECIFICATION forming part of Letters Patent No. 683,833, dated October 1, 1901.

Application filed April 10, 1901. Serial No. 55,202. (No model.)

To all whom it may concern:

Be it known that I, MARSHALL BECK, a citizen of the United States, residing at Moline, county of Rock Island, State of Illinois, have 5 invented certain new and useful Improvements in Machines for Gathering and Loading Hay; and I do hereby declare the following to be a full, clear, and exact description of the invention, such as will enable others 10 skilled in the art to which it appertains to make and use the same.

This invention relates to improvements in that class of hay-loaders that are attached to and drawn by the vehicle on which the hay is 15 to be loaded, the loader in its passage across a field gathering the hay from the ground and delivering it onto the vehicle in a continuous operation.

The general objects of the invention are, 20 first, to provide an improved draft arrangement whereby the loader may be hitched up to and unhitched from the wagon or other vehicle behind which it is to be drawn without requiring the operator to get under the 25 wagon and without the necessity of a nice adjustment of the relative positions of the wagon and loader; second, to so mount the machine upon the ground-wheels as to obviate the necessity of a supporting-axle and allow 30 the employment of a through-shaft that is relieved of all weight and has only the duty of driving the operative parts to perform; third, to combine what may be termed a 35 "double pick-up" with a floating compressor, thereby increasing the gathering action and enlarging the capacity of the elevator to handle the hay; fourth, to provide a novel construction of the compressor itself, whereby it is adapted to yield at any point to adapt 40 itself to the mass of hay on the elevator; fifth, to provide numerous novel details of construction combined and coöperating with the features hereinbefore mentioned in such manner as to produce the best results, all of 45 which will be referred to in detail and hereinafter pointed out in the claims.

The foregoing and such other objects as may hereinafter appear are attained by the devices illustrated in the accompanying drawings, in which—

Figure 1 is a perspective view of a loader

embodiment of my invention. Fig. 2 is an enlarged side elevation of the rear end thereof. Fig. 3 is an enlarged elevation of the upper or discharge end thereof. Fig. 4 is a central longitudinal section through the portion of the machine shown in Fig. 2. Fig. 5 is a central longitudinal section through the portion of the machine shown in Fig. 3. Fig. 6 is a detail of the teeth on the elevating-cylinder. Fig. 7 is a longitudinal section through one end of the elevating-cylinder and its driving mechanism. Fig. 8 is a transverse vertical section on the line 17 17 of Fig. 7. Fig. 9 is a transverse vertical section on the 65 line 18 18 of Fig. 7. Fig. 10 is a detail showing the connection between the compressor-bars and the stripper. Fig. 11 is a sectional elevation more clearly showing the connection between the tongue and loader. Fig. 12 is a 70 perspective view of the complete loader from the rear, and Fig. 13 is a similar view of the entire machine from the left-hand side. Figs. 14 and 15 are respectively end and fragmentary side views of one end of the elevating-75 cylinder. Figs. 16 and 17 are details illustrating the manner of connecting the gathering-fingers to their finger-bars, and Fig. 18 is a detail illustrating the cap by means of which the side bars 60 of the stripper are 80 sleeved upon the shaft of the floating gatherer. Fig. 19 is a perspective detail of the tongue connection.

This machine in a general way comprises features common to machines of this class, 85 such as the triangular frame having the inclined side boards A, between which operates a compressor B and below which travels the upper reach of an elevating-carrier composed of side chains C and slats D, the frame being mounted upon a single pair of ground or traction wheels E, from which is driven the elevating-cylinder concentric with the axes of said wheels and around which works the lower end of the carrier, the upper end of the 90 carrier working, as usual, around a pair of idle pulleys F, mounted in the upper forward end of the frame. To the rear of the elevating-cylinder and suitably carried by the frame is a floating gatherer G, which is 100 also driven from the ground-wheels, while extending forward from the machine is the

usual tongue H, by means of which the loader is attached to the hay-rack, wagon, or other vehicle into which the hay is to be loaded. While these general features are common to 5 several prior machines, their construction and mode of operation in the present machine are entirely novel, so far as I am aware, and not only admirably serve the intended purpose, but avoid numerous objections en- 10 countered by the same features in prior machines of this class when subjected to the exigencies of service.

In this machine there is no main axle in the ordinary sense of that term—that is to 15 say, there is no axle extending between the ground-wheels and upon which the frame of the machine is supported. Instead thereof the shaft of the elevating-cylinder, which in the present machine is a cylinder mounted 20 on an axis coincident with that of the ground-wheels, is a freely-mounted shaft which does not carry any of the weight of the machine, not even that of the cylinder through which it passes and which it drives. On the con- 25 trary, the entire weight of the machine, including the elevating-cylinder and its operating-shaft, is carried directly by the ground-wheels, upon which the frame of the machine has what I call a "wheelbarrow-mount" on 30 each of said wheels. In other words, the hub of each ground-wheel is extended so as to form a hollow trunnion at either side thereof, and upon these hubs the frame of the machine is directly mounted. This is effected 35 by having at each side of the machine a pair of parallel sills I, and between each pair of sills a ground-wheel E is located, each sill having bolted thereto on the under side a bearing-box J, in each of which is journaled a re- 40 duced extension K on opposite ends of the hub L of the wheel. The outer end of the hub, which passes under the outer sill, is pro- 45 longed, so as to project a sufficient distance beyond the sill to receive the hub of a pawl- plate M, which is rigidly mounted thereon either by means of set-screws or other interlocking devices, such as the tongue - and-groove connections N. (Shown more clearly in Fig. 8.) The pawl-plate M, which, in effect, 50 is simply a crank-arm on the wheel-hub, carries a spring-actuated pawl O near the outer end, which is adapted to engage a ratchet-wheel P, whose hub Q is prolonged inwardly and rotates within the bore of the wheel-hub 55 L. Into the bore of the inner end of the wheel-hub rotatively fits the hub of the disk or head R of the elevating-cylinder, which is thus supported directly in the hub of the ground-wheel and which will be described 60 in detail farther on. It is sufficient to here state that the elevating - cylinder has companion heads at opposite ends, the two heads being rigidly connected by the finger-bars S, so as to form a cylinder, the hub of the 65 head at the opposite side of the machine being in all essential respects a duplicate of that shown in Fig. 7 and is journalcd and

supported in the hub of the ground-wheel at the opposite side of the machine. The cylinder-hub and the ratchet-wheel P, with its hub Q, and the pawl-plate M, with its pawl, are preferably duplicated at the opposite side of the machine, the pawl and ratchet-wheel being of course there located beyond the outer sill and the ground-wheel being journaled beneath the pair of sills I in the same manner as shown in Fig. 7. Extending through the hubs of the ratchet-wheels and the hubs of the cylinder-heads is a power-shaft T, which of course extends freely 80 through the bore of each of the ground-wheels, but which is keyed or otherwise non-rotatively secured to the hubs of the ratchet-wheels and heads. In the drawings I have shown the power-shaft square in cross-section and provided the hubs of the ratchet-wheels and of the heads with correspondingly-squared central bores, so as to afford a non-rotative engagement with the shaft without the use of keys or other means for producing 90 this result. It will thus be seen that the power-shaft T has none of the duties of an axle to perform, does not subserve the purpose of an axle, and does not form any part of the frame structure of the machine. No 95 weight is placed upon it, and it has only to perform the duties of a shaft for transmitting power to the driven parts of the machine, being itself freely though indirectly journaled in the hubs of the ground-wheels. 100 The entire weight of the elevating-cylinder is also carried directly by the hubs of the ground-wheels, which feel the weight thereof upon their inner peripheries or bores, while the weight of all the rest of the machine is 105 carried directly upon the outer peripheries of the hubs of the ground-wheels through the intermediacy of the side sills I, each pair of which has a wheelbarrow-mount upon one of the wheels. 110

It will be understood that the free ends of the driving-pawls O at opposite sides of the machine must point forward, so that as the machine is drawn forward upon the ground-wheels they will engage the ratchet-wheels 115 P and rotate the power-shaft T, and consequently drive the elevating-cylinder. When desired, as in traveling from field to field, these pawls may be thrown out of engagement with the ratchet-wheels by springing 120 the ends of their actuating-springs U over the studs V on the pawl-plate, which raises and holds them out of action, in which case they would travel around the ratchets with the pawl-arm and wheel-hub, but allowing 125 the ratchet, the power-shaft, the elevating-cylinder, and the parts driven thereby to remain at rest. All the other driven parts of the loader, particularly the floating gatherer, may be driven either directly or indirectly 130 from the power-shaft; but the power is transmitted from one end of the shaft only, preferably the left-hand end, as shown in the drawings.

A spur-gear W is secured by screws, rivets, or otherwise to the outer face of the left-hand ratchet-wheel and engages a smaller gear X, mounted upon a stud bolted against the face 5 of the outer frame-sill. The direction of rotation of the smaller gear is therefore reverse to that of the larger, and it has cast therewith or riveted to the outer face thereof a driving sprocket-wheel Y, which is connected 10 by a sprocket-chain Z with another sprocket-wheel *a*, rigidly mounted upon the end of the shaft *b* of the gathering-cylinder G. This connection causes this cylinder to rotate in the reverse direction to the elevating-cylinder, 15 so that the opposing sides thereof move in the same direction, while those portions moving over the ground move in opposite directions, as clearly indicated by the arrows in Fig. 2. Thus the elevating-cylinder revolves 20 forward at the ground-line with the travel of the ground-wheels while the gathering-cylinder revolves backward, which causes the side of the elevating-cylinder next to the ground to pass backward over the same while the side 25 of the gathering-cylinder next to the ground passes forward, the combined action of the two cylinders being to pinch the hay between them. It will also be noted that the gathering-cylinder is in a plane somewhat below the 30 elevating-cylinder, so that the latter will pass over the hay upon the ground without engaging the same "rolling" down the high piles, while the gathering-cylinder acts as a rake to initially lift the hay from the ground and 35 deliver it to the elevating-cylinder.

The gatherer is of the floating type—that is to say, it is so supported upon the frame of the machine that it may rise and fall to accommodate itself to the various inequalities 40 of the ground and to ride over and clear obstructions on the ground without damage to itself. It is floated and driven in the following manner: The shaft *b* of the gathering-cylinder is journaled at its ends in a pair of 45 float-bars *c*, which are pivoted at their forward ends to the frame of the machine, the pivot on the left side of the machine being afforded by the stud upon which the sprocket-wheel Y is journaled. From the float-bars *c*, 50 project upward angularly-disposed arms *d*, constituting in effect, when taken in connection with the float-bars, bell-crank levers. The upper ends of the arms *d* are connected by forwardly-extending coil-springs *e* with the 55 frame of the machine, the connection of the springs with the machine being preferably adjustable, so that the spring tension may be varied by some means, such as the threaded eyebolt *f*, into the eye of which the spring hooks, 60 the threaded end of which bolt passing freely through a concaved nut-seat on the cross-frame bar *g* and having mounted thereon a ball-formed threaded nut *h*, having a permanent handle for convenience of manipulation. The 65 rear ends of the float-bars *c* and the upper ends of the bars *d* are connected by another bar *i* into a triangular frame, said bar *i* being perfo-

rated and passing through a loop *j*, secured to the side sill of the machine, so that a pin may be inserted through one or the other of the holes in said bar to limit the downward movement of the gatherer. Of course it will be understood that the bars *d* and *i*, springs *e*, and the spring-adjusting devices will be duplicated at the right-hand side of the machine. It will thus be seen that the gatherer is free to float in spring suspension about the axis of the driving-sprocket thereof, so that the tension of the sprocket-chain by which it is driven will not be affected by any change 80 in its position, and also that by reason of the length of the gathering-cylinder, which in practice is about eight feet, but has very slight play at the pivotal point of the gatherer, will permit the independent rising and 85 falling of the ends of the gatherer, so that should the ground rise under one end and remain level under the other end the work of the gatherer would not be materially interfered with and it would pick up the hay at 90 either end as effectually as at the other. While the rotation of the shaft *b* causes a corresponding rotation of the gatherer-cylinder, at the same time and as a result of such rotation I am enabled to automatically and positively 95 rock the gathering-fingers upon their axes, so that they will be caused to assume various tangential positions with relation to the periphery of the cylinder during their travel about its axis.

The sprocket-wheel *a* is rigidly mounted in any suitable manner upon the shaft *b*, so as to rotate therewith, preferably by having the shaft square in cross-section and fitting in a correspondingly-squared central bore in the 105 sprocket-wheel. The cylinder of the gatherer is composed of a pair of heads at opposite ends thereof, connected by a series of finger-bars *t*, said bars being arranged in a circle about the heads a suitable distance from 110 the outer peripheries thereof, each carrying a series of gathering-fingers extending tangentially therefrom and each being loosely journaled at its ends in said heads, respectively. The finger-bars are rocked in their 115 bearings as the drum rotates by any appropriate means for that purpose, and the fingers are thus caused to change their positions relatively to the periphery of the cylinder as they revolve, projecting radially or 120 vertically in passing nearest the ground and delaying or rocking backwardly as their points rise, so that at the stripping-point their position is practically horizontal and they recede or back out of the hay endwise at substantially 125 a right angle with the stripper. The present invention is not limited to any particular means for producing this rocking motion of the gathering-fingers; but the arrangement which I prefer to employ is that 130 illustrated and described in an application of even date herewith, where the same construction of gathering-cylinder and rocking fingers is employed in a side-delivery rake.

The gathering-fingers, besides having the rocking action just described, are also resili-
ent, being preferably composed of strong
spring-wire and are formed at their inner
5 ends into coils of slightly-greater diameter
than the diameter of the finger-bars *t*. These
coils surround the finger-bars. The inner
end of each coil terminates in a straight end
and is seated in a kerf in the finger-bar and
10 is held firmly therein by any appropriate
means, but preferably by the means de-
scribed in my application first referred to.
Thus while the fingers have sufficient stiff-
ness to perform the comparatively light work
15 of gathering and lifting the hay they can
still readily spring back under the more vio-
lent strain of contact with the irregularities
of the surface, thus permitting the gathering-
cylinder to float closely along the ground in
20 easy reach of the hay and without being vio-
lently tossed up and down, as would inevi-
tably occur in a floated cylinder having rigid
gathering-fingers.

The position of the gathering-fingers at sub-
stantially right angles to the strippers after
25 picking up the hay is clearly shown in Fig.
4, wherein the strippers 7 are shown in their
preferred form, consisting of a series of metal
straps rigidly secured to a stripper-board 8
30 at the extreme rear of the machine, whence
they extend downwardly and curve around
the gathering-cylinder on substantially the
same arc as the periphery of the cylinder and
close to the finger-bars, thus leaving practi-
35 cally the whole length of the gathering-fingers
protruding below the strippers on the
ground side for work and keeping the strippers
as far as possible away from ground con-
tact. The strippers leave the gathering-cyl-
40 inder tangentially at its forward side and ex-
tend to a point considerably above the cyl-
inder, where they are rigidly secured to the
lower compressor-yoke 9. The board 8 and
yoke 9 are connected, braced, and spaced by
45 an intermediate strap 10, oblique rods 50,
and end straps or frame-braces 60, the latter
lying beyond the ends of the gatherer-cyl-
inder and having pivoted or rocking bearings
50 upon the sleeve 1 of the shaft of the cylinder
by means of the caps 11. The strippers and
the connected parts forming their mounting-
frame constitute what may be called the
"stripper-section," and the free rocking
55 mount of this section enables it to act auto-
matically and as an auxiliary compressor in
harmony with the compressor-section proper,
the two sections having a hinged connection,
as will hereinafter be more clearly shown. By
60 this arrangement the strippers are not only
held in fixed relation to the gatherer-cyl-
inder, but move therewith as the gatherer
floats, so as to always be in proper position
to strip the gathering-fingers. The forward
65 reach of the strippers is on a curve substan-
tially corresponding with the elevating-cyl-
inder, although the fingers 12 of the elevat-
ing-cylinder do not reach in between the

strippers and, indeed, do not extend quite
to the strippers, but only close enough to co-
operate with them, so as to form a continu-
ous throat for the elevation of the hay after
it is picked up by the gathering-cylinder for
70 its delivery by the elevating-cylinder to the
space between the elevating-carrier and the
compressor. The fingers 12 of the elevating-
cylinder are slightly-trailed spring-fingers,
75 substantially like the gathering-fingers, each
having a coil 13 formed therein and having
its inner terminal clamped between a pair of
parallel boards 14, which constitute the bars of
80 the cylinder. To each end of each of these bars
is secured a rigid finger 15, as shown more
clearly in Figs. 4 and 7, which fingers lie closely
adjacent to the heads of the cylinder and being
rigid assist the more positively in controlling
85 the hay at the sides of the elevator, where it
tends to mass and delay in the act of being
separated from the hay left on the ground.
These fingers being curved or trailed slightly
90 withdraw into the carrier at an angle suffi-
ciently approaching endwise to strip cleanly
out of the hay. The fingers 12 of the elevat-
ing-cylinder by reason of their flexibility and
trailing form will accommodate themselves
95 to the hay upon the carrier and will lie back
and withdraw gradually from the hay by sub-
stantially endwise movement when necessary,
so as not to disturb the mat or carry down
any of the hay onto the drum.

The elevating-carrier of my machine, like
most other machines of this class, is composed
of a pair of link chains C at opposite sides
thereof, connected at regular intervals by a
series of transverse slats D, such slats being
100 attached at their ends to ears formed upon
appropriate links. I prefer to drive the car-
rier by the slats, simply using the chains as
a means for connecting the slats, and there-
fore so far as any function which these chains
have to perform their construction is imma-
105 terial, and plain bands, belts, or link chains
of any character may be employed. Each
elevating cylinder-head R (see Fig. 7) is pro-
vided with a circumferential flange 16, which
is smooth on its exterior, and at the inner
110 edge a radial flange 17 projects and is pref-
erably curved inward and has therein at regu-
lar intervals notches 47, (see Figs. 2, 4, and
14,) into which fit the slats D of the carrier,
the chains C of the carrier running upon the
115 flanges 16. Between the heads of the cyl-
inder and secured to the bars 14 is one or more
auxiliary driving-rings 48, having lugs 18,
which are backwardly curved on their for-
ward faces and arranged to lie just back of
120 the slats when properly engaged by the heads
of the cylinder. These auxiliary drivers af-
ford rests for the long slats at one or more
intermediate points and at the same time as-
sist in driving, and thereby prevent undue
125 bending of the slats when a heavy load is
placed thereon. I also prefer to connect the
slats at regular intervals by slack ropes,
which are substantially parallel with the

chains C. These ropes are simply for the purpose of forming a better support for the mat of hay during its elevation and serve to act as auxiliary stripping devices in conjunction with the slats for properly disengaging the hay from the elevating-fingers. The proportion and arrangement of these fingers and the slats of the carrier is such that a slat will time in between each pair of bars 14, so that 5 in coöperating with the gatherer to pick up the hay the fingers will project almost wholly beyond the slats; but after carrying the hay up until it is firmly engaged between the carrier and the compressor the fingers begin to 10 gradually withdraw from the mat of hay as the carrier leaves the elevating-cylinder at a tangent, the fingers trailing and yielding as may be necessary to withdraw from the hay without liability of carrying any of the hay 15 down with them to wrap around the elevating-cylinder. As indicated in Fig. 7, the inner sills I of the loader-frame are quite close to the outer edge of the flanges 16 of heads R, and the sills where they extend forwardly 20 of the heads, as shown in Fig. 4, serve as guides to direct the descending ply of the carrier-belts onto the flanges and have also the function of holding the belts on the flanges and preventing lateral displacement. 25 The compressor in my present machine consists of a series of long bars 19 and 23, lying edgewise substantially parallel to the upper reach of the carrier and in a plane slightly above the same. Each of the bars 19 has a 30 pivotal or hinge connection at its lower end with the corresponding one of the strippers 7, the stripper being bent rearwardly just below the lower compressor-yoke 9 to form a shoulder for a strap 20 (secured to the end of 35 the compressor-bar 19) to rest upon, the stripper also passing loosely and freely through the loop, so as to permit a pivoting or hinging action of the loop between the bend in the stripper and a cleat 21 on the stripper 40 above the shoulder, as clearly shown in Fig. 45 10. The side bars 23 of the compressor project at their lower ends outside the carrier and are connected by braces 24 directly with the lower compressor-yoke 9 by a pivot connection 25, so that they clear the rims of the traction-wheels far enough to permit the hay at the sides to pass freely and yet do not interfere with the flexibility of the connection between the compressor and the stripper. 50 The upper ends of all the compressor-bars are provided with elongated bales or loops 26, which pass through eyes in the lower ends of hangers 27, depending from an upper compressor-yoke 28, the loop connection permitting 55 the bars to slide endwise bodily forward or back above the face of the carrier independently of the movement of the yoke, as required in coöperating with the stripper and the gatherer. The yoke is rigidly connected 60 by brackets 29 to the free end of an outside arm 30, which is pivotally connected at its lower end 31 with the side frame of the ma-

chine. The outside arms 30 at their forward ends rest normally upon a suitable bracket or shoulder 31 on the machine-frame, so as 70 to support the upper compressor-yoke 28, and consequently the upper ends of the arms, at a fixed minimum distance above the upper end of the carrier, keeper-loops 32, attached to the machine-frame, being provided around 75 the outside arms 30 to serve as guides and upward stops therefor in their vibration.

It will be seen that the preponderance of weight of the stripper is forward of its rocking seat on the gatherer-cylinder axis and 80 that this preponderance is augmented by the weight of the lower ends of the compressor-bars. To support this forward weight and to prevent the hinge-connected ends of the stripper and compressor from falling down upon 85 the face of the carrier, the yoke 9, from which the other parts depend, is given an independent swinging seat or downstop on the main frame or, as preferred and shown herein, on the floating frame near its pivot on the main 90 frame. This independent stop is provided by rods 22, which are pivotally mounted at their lower ends on the floating frame-pieces d, their upper free ends working through eyes secured to the ends of the yoke. Cotter-pins 95 through said rods above and below the eyes (see Fig. 13) constitute upper and lower limits for the movement of the yoke, the rods being provided with a series of holes for the cotter-pins, so that the range of action of the 100 yoke may be adjusted to the requirements of the work being done, and the rods being encircled by coil-springs 122 to hold the yoke down with an elastic pressure, which may be varied by adjusting the upper cotters. The 105 compressor when not at work or when working in thin hay thus rests its upper and lower yokes on downstops which hold it within a few inches of the carrier-face and substantially parallel with the carrier, but also, by 110 reason of its yokes being freely mounted on the downstops, the hay can lift it at either end, side, or corner, substantially providing the exact amount of room required by the varying volume of the elevating hay and 115 maintaining an equalized compression by the 120 tilting of the compressor to adapt itself to the unequal distribution of the hay in the elevator at any given time.

By trailing and pivoting the gatherer on the main frame, by rock-seating the stripper-section on the gatherer - cylinder axis, by hinging together the forward end of the stripper - section and the rear end of the compressor-section, by supporting the forward 125 weight of the stripper-section, increased by the compressor-weight at that point, on the backward and forward swinging stop-rods brought up from the main or floating frames, by slidably suspending the compressor-bars 130 under their upper yoke, and by pivoting the supporting-arms of this yoke back on the main frame there is provision for every possible movement necessary in the parts so re-

lated, no matter how extreme the variations in service may be. As the gathering-cylinder is mounted in a position substantially horizontal to the pivot of its floating frame 5 and the lower compressor-yoke in a position substantially vertical thereto, the parts being connected and both supported from the floating frame, it follows that when the gatherer floats up and down in passing over surface elevations the yoke must move forward and back in a like arc of a circle around the pivot of the floating frame, since the gatherer and yoke have the same relative movement as the horizontal and vertical spokes in a revolving wheel. The forward-and-back movement of the yoke is permitted by the swinging mount of the stop-rod supporting it, and the compressor-bars supported upon the yoke are moved by its oscillations up and down 10 the carrier-face, their endwise shift being permitted by their sliding-loop connection with their upper yoke. During the endwise movement of the compressor-bars their parallel position to the carrier-face is substantially maintained by means of the parallel slides at the topend and of the substantially parallel movement of their lower yoke on the swinging stop-rods. With the gatherer up 15 and the lower yoke down the compressor-bars have made their extreme forward and endwise movement. If while maintaining these relative positions an excessive quantity of hay should lift the extreme top end of the compressor, the upper yoke would come down 20 the sliding loops sufficiently to compensate for the difference in the arcs, respectively, in which the yoke and the bars were rising. This position of all the parts determines the relative location of the lower ends of the sliding loops, as to set them higher up the bars would lock the parts from taking the various compensating positions necessary to work. If while the gatherer and the upper yoke are 25 in their highest positions the lower yoke be raised as part of the stripper-section, it would rock toward the rear, drawing the compressor-bars endwise down the carrier-face until the sliding loops would hang about centrally under the upper yoke. With the lower yoke 30 up and the gatherer and upper yoke down the compressor-bars have made their extreme rearward and endwise movement and the upper yoke its extreme forward movement. This position of the parts determines 35 the relative location of the upper ends of the sliding loops to avoid locking. With the lower yoke dropped down also—that is, all parts on their lower stops, as shown in Fig. 13—the bars and slide-loops move forward to 40 their middle positions the same as when all parts are raised to their limits. Owing to the looseness of all the pivot and hinge connections involved and to the considerable width of the machine all these varying positions 45 can be taken at one side of the machine, while the corresponding parts at the other 50 side are at rest or making other combinations, as the work may require.

In mounting the loader on two wheels the preponderance of weight is necessarily and naturally forward, and to support the machine when not attached to a wagon or not in use a swinging leg 33, attached to the frame of the machine forward of the wheels and below the carrier, is let down to rest 55 upon the ground. While at work the swinging leg is hooked up under the stub-tongue 34 (see Fig. 11) by any convenient means, such as the chain and fork shown in Figs. 1 and 19, and the tongue H is attached by any 60 suitable means to the wagon-reach. The tongue H is attached to the stub-tongue 34 at its rear only by the leveling-stirrup 35, which straddles the stub-tongue with its upper free ends, which are perforated, so that a 65 pin 36 may be passed through perforations in the stirrup ends and through a slide 37, attached to the under side of the stub-tongue. The slide in effect, constitutes a long slot, so that the tongue H may be moved backward 70 and forward longitudinally, the leveling-bolt constituting a pivot therefor. At the forward end of the stub-tongue there is secured a transverse bar 38, provided at opposite ends with handles 388. (See Fig. 19.) The bar 75 is notched on its under side at 39 to receive the tongue H, which is provided with an elongated slot 40 in its upper face, preferably covered with a metallic wear-plate, which also is a draft-plate and divides the slot into 80 two parts, as clearly shown in the drawings, and down into one or the other parts of this slot projects the end of a draft pin or stud 41, depending from the stub-tongue just back of the handle-bar. In Fig. 1 the tongue H 85 is shown in dotted lines as resting with its forward end upon the ground out of working position, and the swinging leg 33 is also down on the ground to support the machine. In Fig. 11 and in full lines in Fig. 1 the 90 tongue is shown up in a horizontal position, as when attached to a wagon at its forward end. In this position the machine is supported by the wagon-reach r, to which the forward end of the draft-tongue is secured, 95 preferably by means of a bar r', suspended from the reach and extending through the socket r² on the end of the tongue, the connection between the bar and the socket being made by a clevis r³, that is adjustably 100 pivoted to the bar and is caught under the hook r⁴ on the socket. The object of this arrangement is to avoid the necessity of going under the wagon to hitch or unhitch the loader. When the wagon is loaded, the first 105 act in unhitching the loader is to let down the leg 33 and by means of the handle 388 to lift up the frame, so that the leg will straighten out and support the loader sufficiently above and free of the draft-tongue to 110 effect the disengagement of the draft-stud 115 from the socket. This leaves the draft-

tongue supported by the clevis r^3 at its front end and the leveling-pin 36 at its rear, and immediately that the stud 41 is free of the socket 40 the slide 37 permits the weight of the tongue to cause it to lurch or swing ahead, thus bringing the bar so that it hangs vertically and loosely within the socket. The draft strain being thus removed from the interlocking parts, a quick lift of the tongue 10 hooks the clevis and tosses its free end out of the path of the hook long enough to permit the socket to drop from the bar. In hitching up the loader the operator has only to bring the socket r^2 in line with the point 15 of the bar r' and lift the front end of the tongue. As the socket rises the hook r^4 passes the clevis and the latter drops under the hook by its own weight. As will be understood, the pole bears no weight either 20 when hitching or unhitching, and being free to move endwise and sidewise by means of the slide 37 it is easy to get the hitch parts into line with each other, and no great care is required to adjust the wagon to the loader.

25 It is obvious that numerous changes in the form and construction of the various parts of my machine may be made without departing from the spirit of my invention, and all such changes are contemplated by the following 30 claims. It will also be understood that some of the features of the invention are applicable to any machines which gather the hay from the ground, whether they load it upon wagons or other vehicles for transportation 35 or merely gather it for the purpose of raking or tedding it, especially the manner of mounting the frame and driving the parts and the construction and manner of supporting the floating gatherer.

40 Having thus described my invention, what I claim is—

1. In a hay-loader, the combination of a stub-tongue rigid with the loader-frame, a draft-tongue having a disconnectable draft 45 connection with said tongue, and a sliding pivotal connection between the draft-tongue and the stub-tongue.

2. In a hay-loader, the combination of a stub-tongue rigid with the loader-frame, a 50 folding leg pivoted to the tongue and adapted to support the frame in a slightly-elevated position, a draft-tongue having a disconnectable draft connection with the stub-tongue, and a sliding pivotal connection between the rear end of the draft-tongue and the stub-tongue.

3. In a hay-loader, the combination of a stub-tongue rigid with the loader-frame, a 55 cross-bar at the front end of the tongue having handles by means of which the loader-frame may be lifted, a pivoted foldable leg adapted to support the frame in a slightly-raised position, a depending draft-stud, a draft-tongue having a sliding pivotal connection with the stub-tongue at its rear end, and a socket or sockets in the upper side of

the draft-tongue located and adapted to receive the draft-stud on the stub-tongue.

4. In a machine for gathering hay, the combination of axleless ground-wheels, extensions of the hubs of said wheels upon which the frame of the machine is mounted, a driving-shaft for the operative parts of the machine journaled in said wheel-hubs, and a driving connection from the wheel-hubs to 75 the shaft.

5. In a machine for gathering hay, the combination of a pair of parallel frame-bars at the side of the machine, a ground-wheel having its hub provided with extended ends upon 80 which said bars are supported with the wheel between them, a driving-shaft journaled in the hub of said wheel, driving connections from the shaft to the operative parts of the machine, and a driving connection between 85 the wheel-hub and the shaft.

6. In a machine for gathering hay, the combination of a pair of parallel frame-bars at opposite sides of the machine, ground-wheels having their hubs provided with extended 90 ends upon which said bars are supported with the wheels between them, a through-shaft for driving the operative parts of the machine journaled in the hubs of said wheels, and a disconnectable driving connection between 95 said wheel-hubs and the shaft.

7. In a machine for gathering hay, the combination of a pair of parallel frame-bars at opposite sides of the machine, ground-wheels having their hubs provided with extended 100 ends upon which said bars are supported with the wheels between them, a through-shaft journaled in said wheel-hubs, a cylinder carried by said wheels and having elevating-fingers, an oppositely-rotating cylinder carried 105 by the loader-frame in rear of the wheels and having gathering-fingers, an elevator receiving the hay gathered by said cylinders, connections whereby the two cylinders and the elevator are driven by the shaft, and driving 110 connections between the shaft and the ground-wheels.

8. In a machine for gathering hay, the combination of axleless ground-wheels, an elevating-cylinder having a journaled connection 115 with the hubs of said wheels, a driving connection between the cylinder and the wheels.

9. In a machine for gathering hay, the combination of axleless ground-wheels, an elevating-cylinder provided with journals having 120 bearings in the hubs of said wheels, a shaft extending through the journals of the cylinder, and a driving connection between the shaft and the ground-wheel hubs.

10. In a machine for gathering hay, the combination with the side bars of the machine-frame, of axleless ground-wheels having hub extensions upon which said side bars are supported, a driving-shaft for the operative parts of the machine journaled in said wheel-hubs, 125 driving-gears fixed upon said shaft outside the frame-bars, and a driving connection be-

- tween the outer extensions of the wheel-hubs and the driving-gears.
11. In a hay-loader, an elevating-cylinder composed of heads at opposite sides of the machine, finger-carrying bars extending between the heads, rigid fingers carried by said bars adjacent to the heads, and elastic fingers along the bars between the rigid fingers.
12. In a hay-loader, the combination of an elastically-suspended floating frame, a rotating fingered cylinder mounted in said frame, and a stripper composed of transverse bars in front and rear of the cylinder, with straps connected at their opposite ends to said bars and passing close beneath the cylinder, said cross-bars being connected together by side bars that are sleeved on the shaft of the cylinder so as to permit the stripper to rock about the cylinder-axis.
13. In a hay-loader, the combination of an elastically-suspended floating frame, a rotating fingered cylinder mounted in said frame, and a stripper composed of transverse bars in front and rear of the cylinder, with straps connected at opposite ends to said bars and passing close beneath the cylinder, said cross-bars being connected together by side bars that are sleeved on the shaft of the cylinder so as to permit the stripper to rock about the cylinder-axis, and the upper bar being free to rise and fall independently of the floating frame and cylinder.
14. In a hay-loader, the combination of an elastically-suspended floating frame, a rotating fingered cylinder mounted in said frame, and a stripper composed of transverse bars in front and rear of the cylinder with straps connected at opposite ends to said bars and passing close beneath the cylinder, the floating frame and its gathering-cylinder being adapted to rise and fall independently of the front bar.
15. In a hay-loader, the combination of an elastically-suspended floating frame, a rotating fingered cylinder mounted in said frame, and a stripper composed of transverse bars connected together by straps passing close under the cylinder, the front cross-bar being free to move vertically with respect to the floating frame, and the rear one being connected to move with the floating frame.
16. In a hay-loader, the combination of a floating frame pivoted to the main frame and elastically supported at its rear end, a rotating fingered gathering-cylinder carried by said frame, and a stripper for the fingers of said cylinder, said stripper being composed of transverse bars connected together by straps passing close under the cylinder, the front transverse bar being vertically movable so as to permit the straps to have a movement about the axis of the cylinder.
17. In a hay-loader, the combination of a fingered elevating-cylinder carried by the main frame, an auxiliary fingered gathering-cylinder in rear thereof carried by an elastically-suspended floating frame, an elevator to which the hay gathered by the co-operation of the elevating and gathering cylinders is delivered, and a stripper for the fingers of the gathering-cylinders, said stripper being composed of transverse bars in front and rear of the cylinder connected together by straps passing close beneath the cylinder, and curving upwardly and forwardly over the elevating-cylinder, the front cross-bar being adapted to yield vertically away from said elevating-cylinder.
18. In a hay-loader, the combination of a fingered elevating-cylinder carried by the main frame, an auxiliary fingered gathering-cylinder in rear thereof carried by an elastically-suspended floating frame, an elevator to which the hay gathered by the co-operation of the cylinders is delivered, and a stripper for the fingers of the gathering-cylinder, said stripper being composed of transverse bars in front and rear of the cylinder connected together by straps passing close beneath the cylinders, and curving upwardly and forwardly over the main-frame cylinder, and at that point having a hinge connection with a yielding compressor overlying the elevator, the front cross-bar being adapted to yield vertically away from the main-frame cylinder.
19. In a hay-loader, the combination with the elevator, of an elevating-cylinder mounted in the main frame at the foot of the elevator, a floating elastically-supported frame carrying an auxiliary gathering-cylinder below and in rear of the elevating-cylinder, and means for rotating said cylinders in opposite directions.
20. In a hay-loader, the combination with the elevator, of an elevating-cylinder mounted on the main frame in fixed position relative to the elevator and the ground, and a floating elastically-supported frame carrying an auxiliary gathering-cylinder whose position is automatically variable relative to the ground, the fixed cylinder and the elevator.
21. In a hay-loader, the combination with the elevator, of an overlying compressor, a yoke at the head of the elevator, and sliding connections between the compressor-bars and the yoke, said yoke being carried by arms pivoted to the elevator-frame, whereby it is free to rise.
22. In a hay-loader, the combination with the elevator, of an overlying compressor, a yoke at the foot of the elevator, and connections between the yoke and the compressor-slats, the yoke being adapted to rise and fall.
23. In a hay-loader, the combination with the elevator, of an overlying compressor, a yoke at the foot of the elevator connected to the compressor, vertical rods pivoted on the elevator-frame, and having a sliding connection with the yoke, and springs to hold the yoke down with an elastic pressure.
24. In a hay-loader, the combination of a

floating fingered gathering-cylinder, a stripper for the fingers of said cylinder, an elevator, an overlying compressor for the elevator, and a flexible connection between the lower 5 end of the compressor and the upper end of the stripper.

25. In a hay-loader, the combination of an elevator, an elevating-cylinder, mounted in fixed position on the frame at the foot of the 10 elevator, an auxiliary gathering - cylinder mounted in a pivoted floating frame in rear of the elevating-cylinder, a stripper for the fingers of the gathering-cylinder, said stripper being connected to the main frame so as 15 to move with the floating frame, a compressor overlying the elevator carrier-belt, and a pivotal connection between the compressor and the stripper.

26. In a hay-loader, the combination of the 20 main frame, a floating cylinder mounted in arms pivoted on the frame and having gathering-fingers, and a stripper for the fingers of the gathering-cylinder, said stripper consisting of straps connected to cross-bars in 25 front and rear of the gathering-cylinder, and said stripper being pivotally mounted on the

axis of the cylinder and free to oscillate and move vertically at its forward end.

27. In a hay-loader, the combination of the main frame having side bars, supporting-wheels journaled in boxes on the under side of said bars, a slatted elevator-carrier having chains, an elevating-cylinder mounted coaxially with the supporting-wheels, and heads at opposite ends of said cylinder having radial flanges provided with notches to receive the slats at intervals around their circumference, and circular rims outside of said flanges on which the carrier-chains run, the cylinder-heads being inclosed between the side bars 30 of the frame, which extend forwardly of the supporting-wheels and in such proximity to the heads that the chains of the descending 35 plies of the carrier will be guided to and held upon the peripheral rim of the heads. 40

In testimony whereof I affix my signature 45 in presence of two witnesses.
